Patented Nov. 4, 1958

183,857

COMBINED TOP AND REAR CONTROL PANEL FOR A WASHING MACHINE OR SIMILAR AR- TICLE

Stuart G. Mundt, North Syracuse, N. Y., assignor to The Murray Corporation of America, Syracuse, N. Y., a corporation of Delaware

Application June 12, 1957, Serial No. 46,564

Term of patent 3½ years

(Cl. D49—1)

Figure 1 is a perspective view of a combined top and rear control panel for a washing machine or similar article;

Figure 2 is an enlarged fragmentary sectional view taken on the line 2—2 of Figure 1; and

Figure 3 is an enlarged fragmentary end elevational view taken from the left hand side of Figure 1.

I claim:

The ornamental design for a combined top and rear

control panel for a washing machine or similar article, substantially as shown.
